US00D752371S

(12) **United States Design Patent**
Do et al.

(10) **Patent No.:** **US D752,371 S**
(45) **Date of Patent:** **** Mar. 29, 2016**

(54) **DISPLAY UNIT**

(71) Applicant: **Samsung Electronics Co., Ltd.,**
Suwon-si (KR)

(72) Inventors: **Kyoung-Sub Do**, Seoul (KR); **Seo-Gyun Kim**, Suwon-si (KR); **Sung-Su Park**, Seoul (KR)

(73) Assignee: **Samsung Electronics Co., Ltd.,**
Suwon-si (KR)

(**) Term: **14 Years**

(21) Appl. No.: **29/510,455**

(22) Filed: **Nov. 28, 2014**

(30) **Foreign Application Priority Data**

Jun. 5, 2014 (KR) 30-2014-0027682

(51) **LOC (10) Cl.** **06-06**

(52) **U.S. Cl.**
USPC **D6/678**

(58) **Field of Classification Search**
USPC D6/657, 661, 661.3, 663, 668, 672, 678,
D6/691, 691.3; D14/340; D19/90; D20/10,
